UNITED STATES PATENT OFFICE

JAMES SYLVESTER CUFF, OF NEW LONDON, CONNECTICUT

CARBURETOR

Application filed January 30, 1929. Serial No. 336,075.

This invention relates to carburetors such as are used in conjunction with internal combustion engines.

Some of the objects of the present invention are: to provide a carburetor in which the liquid fuel and air supplied to an internal combustion engine are controlled simultaneously so as to obtain an economy in the use of liquid fuel, yet a rich mixture; to obtain substantially only liquid fuel for priming the engine; to obtain the proper mixture or gas for the engine when it is desired to allow it to idle; to obtain a fuel mixture of air and liquid fuel in the form of a gas, in a single operation; and to cut off the supply of liquid fuel while admitting air only to the engine in a single operation, so as to convert the engine into an air compressor for the purpose of holding the vehicle with an action similar to that of a brake, while obviating a vacuum in the cylinders which ordinarily draws in oil from the crank case resulting in carbon and waste oil in the cylinders, which is also obviated.

The nature of the invention and its distinguishing features and advantages will appear when the following specification is read in connection with the accompanying drawings, in which—

Figure 1 is an elevation of a carburetor embodying the present invention.

Fig. 2 is a sectional view taken on the line 2—2 of Fig. 1.

Fig. 3 is a transverse sectional view taken on the line 3—3 of Fig. 1.

Referring now more particularly to the several views of the drawing, it will be apparent that, the carburetor in the present instance will include a casing 10 formed to provide a flange 11 by virtue of which the carburetor is attached to the intake of the usual manifold of an internal combustion engine, an air inlet 12, and a mixing chamber 13 in communication with the air inlet 12.

45 A liquid fuel inlet 14 is arranged within the

mixing chamber 13. The air inlet 12 is controlled by a choke valve 15 which is arranged between the inlet 12 and the mixing chamber 13. The choke valve 15 includes a rotatable shaft 16. The liquid fuel inlet 14 is controlled by a valve, which in the present instance, includes a valve member 17 having the usual pointed end 18 which coacts with a tapered seat 19 to control the flow of liquid fuel through the passage 20 of the inlet 14. 50 The said inlet 14 will be connected to the usual liquid fuel supply float chamber. The valve controlling the inlet 14 also includes a block or nut 21 in threaded engagement with the threaded stem of the valve member 17, 55 and a jamb nut 22 also threaded on said stem to aid in holding the nut 21 in the desired adjustment. The valve member 17 is arranged in a bore 23 of an extension 24 on the inlet 14. A sleeve 25 surrounds the stem of 60 the valve member 17 and is arranged between the end portion of the nut 21 and a spring 26 which also surrounds the stem and has one end in engagement with a collar 27 while its opposite end is in engagement with the 65 sleeve 25. The spring 26 constantly acts on the collar 27 to yieldingly maintain the end 18 of the valve member on its seat 19 to cut off the flow of liquid fuel. The outer end of the valve member 17 has connected thereto 70 a wire 28 which leads to a convenient point on the dashboard so that the operator of the vehicle may retract the valve member 27 for priming the engine by allowing liquid fuel to pass out of the inlet 14 while the choke 75 15 is in a closed position.

Suitable operating means is provided for simultaneously operating the valve member 17 and the choke valve 15. The said operating means, in the present instance includes a bell crank lever 29, the arm 30 of which has connected thereto a rod or the like 31 leading to a control device such as the foot accelerator, and the arm 32 of said lever 29 is connected to an arm 33 on one end of the shaft 16 by an 80 85 90

adjustable element 34. The arm 33 has connected to one end thereof a member 35 by screw bolts 36, which extend respectively in slots 37 in the arm 33. The member 35 is formed with an extension in the form of an arcuate and tapered portion or cam 38. The said cam 38 is adapted to coact with one end of the block or nut 21 on the stem of the valve member 17 in response to the movement of the lever 29 to either move the end 18 off of its seat 19, or to allow the spring 26 to function to bring the end 18 on the seat 19. By providing the bolts 36 and slots 37 the cam 38 may be adjusted so as to vary the extent of movement of the valve member 17. The nut 21 may also be adjusted to vary the action of the spring 26. Thus provision is made for obtaining a proper working condition of parts of the device which control the supply of liquid fuel. As the lever 29 is moved in one direction to retract the valve member 17, the choke valve 15 will be moved at the same time to opened position. Air will then be permitted to enter the mixing chamber 13 through the inlet 12 to be mixed with the liquid fuel sucked from the inlet 14, and as a consequence, a full and rich mixture of gas will be passing to the intake manifold of the engine. When the lever 29 is moved by manipulating the rod 31 to move the choke valve 15 to a closed position, the cam 38 will be moved to a position so that the spring 26 can function to move the end 18 of the valve member 17 to a partly opened position, with respect to the seat 19, to allow a small amount of liquid fuel to be sucked in by the engine for the purpose of priming the engine.

Means is provided for controlling the operation of the means which serves to operate the choke valve and the valve controlling the inlet 14. The said control means, in the present instance, consists of a member 39 secured to the casing 10 in any suitable manner and the said member 39 is formed to provide a stop 40, which is in fact, a first fixed stop, and a stop 41, which is in fact, a second fixed stop, and there is provided a movable stop 42 which is adapted to coact with the stops 40 and 41. The stop 42 is carried by the arm 33 and has a nut 43 at one end, a head 44 at the opposite end between which and the arm 33 is arranged a spring 45. A flexible element in the form of a wire 46 is connected to the end of the stop 42 having the nut 43 thereon. The nut 43 serves for adjusting the stop 42 to vary its longitudinal movement in one direction. The spring 45 has a normal tendency to yieldably hold the stop 42 in a normal extended position so that as the arm 33 is moved clockwise, the head 44 will engage the stop 40. The choke valve is in a closed position and the valve member 17 is in a partly opened position when the stop 42 engages the stop 40. By retracting the stop 42 by pulling on the wire 46, the arm 33 may be moved

to such a position as to move the choke valve 15 to an open position, while allowing the valve member 17 to be moved to a closed position. Under this arrangement liquid fuel will be prevented from entering the mixing chamber, and air will be allowed to pass through the inlet 12 to be sucked into the engine cylinders, and this without creating a vacuum which results in oil being drawn into the cylinders from the crank case which ultimately causes carbon to exist in the cylinders. The engine then operates like an air compressor and therefore acts as a brake for the automobile. When the arm 33 is retracted in a counter-clockwise direction to its extreme limit of movement in that direction, the choke valve 15 will be in an opened position while the valve 17 will be fully retracted to allow the full charge of both liquid fuel and air to pass into the mixing chamber, to be there thoroughly mixed prior to its being sucked, in the form of gas, into the intake manifold.

In order to provide a satisfactory mixture or gas for the engine while idling, there is provided in the wall of the casing 10 an air port 47 which is controlled by an element 48 in the form of a screw, one end of which is movable into and out of the port 47, the latter being in communication with ducts 49 through which air passes to the port into the mixing chamber 13. When the valve 15 is in a closed position, the valve member 17 will be in a partly opened position, and the air sucked in through the port 47 will mix with fuel passing out of the inlet 14 thereby producing a satisfactory fuel mixture for keeping the engine running idle.

I claim:

1. In a carburetor, a casing forming an air inlet and a mixing chamber, a choke valve controlling said air inlet, a liquid fuel inlet between the air inlet and the mixing chamber, a valve controlling said liquid fuel inlet, said valve including a valve member, a seat with which said valve member coacts; an adjustable nut on said valve member, a cam supported for movement to coact with said nut, means for effecting the movement of the cam in one direction to move the valve member off of its seat, means constantly acting on said valve member to move it to closed position on its seat and to yieldably hold the valve member on its seat, and means connected directly with said valve member to move it off of its seat.

2. In a carburetor, a casing forming an air inlet and a mixing chamber, a choke valve controlling said air inlet, a liquid fuel inlet between the air inlet and the mixing chamber, a valve controlling said liquid fuel inlet, said valve including a valve member, and a seat with which said valve member coacts; an adjustable nut on said valve member, a

cam supported for movement to coact with said nut, operating means for effecting the movement of the cam in one direction to move the valve member off of its seat, and means constantly acting on said valve member to move it to closed position on its seat and to yieldably hold the valve member on its seat, said operating means being connected to said choke valve so as to move the latter to opened and closed positions in response to the operation of said operating means in the movement of said cam.
